(57) **CLAIM**

The ornamental design for a hair styling apparatus, as shown and described.

DESCRIPTION

FIG. 1 is a left side view of a hair styling apparatus, according to the present invention;

FIG. 2 is a right side view of the hair styling apparatus of FIG. 1;

FIG. 3 is a perspective view of the hair styling apparatus of FIG. 1;

FIG. 4 is a front view of the hair styling apparatus of FIG. 1; FIG. 5 is a rear view of the hair styling apparatus of FIG. 1; FIG. 6 is a top view of the hair styling apparatus of FIG. 1; FIG. 7 is a bottom view of the hair styling apparatus of FIG. 1;

FIG. 8 is a left side view of another embodiment of a hair styling apparatus;

FIG. 9 is a right side view of the hair styling apparatus of FIG. 8;

FIG. 10 is a perspective view of the hair styling apparatus of FIG. 8;

FIG. 11 is a front view of the hair styling apparatus of FIG. 8; FIG. 12 is a rear view of the hair styling apparatus of FIG. 8; FIG. 13 is a top view of the hair styling apparatus of FIG. 8; and,

FIG. 14 is a bottom view of the hair styling apparatus of FIG. 8.

The broken lines showing bristles, parts of the handle, and cord illustrate portions of the apparatus that form no part of the claimed design.
